(57) CLAIM

The ornamental design for a manicure dryer, as shown and described.

DESCRIPTION

FIG. 1 is a top left perspective view of a manicure dryer showing my new design;

FIG. 2 is a top view thereof;

FIG. 3 is a top right perspective view thereof;

FIG. 4 is a left side view thereof;

FIG. 5 is a front view thereof;

FIG. 6 is a right side view thereof;

FIG. 7 is a back view thereof;

FIG. 8 is a bottom left perspective view thereof;

FIG. 9 is a bottom view thereof; and,

FIG. 10 is a bottom right perspective view thereof.

The broken lines shown in the drawings illustrate unclaimed portions of the manicure dryer and form no part of the claimed design.
